SHEET METAL

Franz Wagner, Chicago, Ill., assignor to Ekco Products Company, Chicago, Ill., a corporation of Illinois

Application September 27, 1949, Serial No. 5,179

Term of patent 14 years

(Cl. D54—2)

To all whom it may concern:

Be it known that I, Franz Wagner, a citizen of the United States, residing at Chicago, county of Cook, State of Illinois, have invented a new, original, and ornamental Design for Sheet Metal, of which the following is a specification, reference being had to the accompanying drawing, forming part thereof.

Fig. 1 is an elevational view of sheet metal, showing my new design.

Fig. 2 is an enlarged fragmentary elevational view taken along a portion of any peripheral edge of the article shown in Fig. 1.

Fig. 3 is an enlarged fragmentary section of said article taken on line 3—3 of Fig. 1 in the direction of the arrows.

I claim:

The ornamental design for a sheet metal, as shown.

FRANZ WAGNER.
